[57] CLAIM

The ornamental design for a combined typewriter and
graphmaker, as shown and described.

DESCRIPTION

FIG. 1 is a perspective view of the front, top and one
side of a combined typewriter and graphmaker showing
our new design with the cover closed;

FIG. 2 is a perspective view showing the bottom, rear
and opposite side thereof; and

FIG. 3 is a perspective view similar to FIG. 1 with the
cover open.
